UNITED STATES PATENT OFFICE.

WILLIAM J. KENNEY, OF WILMETTE, ILLINOIS, ASSIGNOR TO UNDERFEED STOKER COMPANY OF AMERICA, OF CHICAGO, ILLINOIS, A CORPORATION OF NEW JERSEY.

DRYING PLANT.

1,172,291.

Specification of Letters Patent. Patented Feb. 22, 1916.

Application filed March 2, 1912. Serial No. 681,231.

To all whom it may concern:

Be it known that I, WILLIAM J. KENNEY, a citizen of the United States, residing at Wilmette, county of Cook, State of Illinois, 5 have invented a certain new and useful Improvement in Drying Plants, and declare the following to be a full, clear, and exact description of the same, such as will enable others skilled in the art to which it pertains 10 to make and use the same, reference being had to the accompanying drawings, which form a part of this specification.

My invention relates in general to the art of drying various kinds of wet or damp 15 materials by means of hot gases passed over the same; and it has for its object to produce a drying plant or apparatus which shall be efficient in operation and which will leave the material which has been dried in 20 the best possible condition. Where the material to be dried is in a loose condition, as in the case of pulpy, fibrous, powdery or granular material, the drying chamber may form part of the apparatus containing the 25 furnace or heat-producing means; but it may sometimes happen that the drying operation must be otherwise conducted and in such cases my invention may be regarded 30 as comprising a simple and economical means of producing a large volume of heated gases.

The various features of novelty whereby my invention is characterized will herein-after be pointed out with particularity in 35 the claim; but, for a full understanding of my invention and of its object and advantages, reference may be had to the following detailed description taken in connection with the accompanying drawings, 40 wherein:

Figure 1 is a longitudinal vertical section through a drying plant arranged in accordance with a preferred form of my invention; Figs. 2 and 3 are respectively 45 sections on lines 2—2 and 3—3 of Fig. 1; Fig. 4 is a transverse horizontal section, on a larger scale than Figs. 1 to 3, through the furnace; and Fig. 5 is a partly front elevation and partly a section on line 5—5 of 50 Fig. 4.

In the drawings I have illustrated my invention as embodied in a plant for drying the pulp remaining after the sugar has been extracted from beets. This pulp possesses 55 a high food value when used as a food for

stock and cattle; but to put the pulp in a satisfactory commercial form it must be dried and the drying must be accomplished in such a manner as not to produce burning and preferably without producing discoloration. Furthermore the drying must be accomplished in such a manner as to prevent the pulp from being tainted and becoming unpalatable to stock and cattle. Consequently a drying plant for beet pulp may 60 be regarded as involving substantially all of the problems of care and economy which are apt to be encountered in drying material of any kind; and therefore I shall confine the detailed description to this particular 65 type of plant although it will of course be understood that I do not desire to be limited to any particular field or class of goods to be treated.

Referring to the drawings, 1 represents a 70 furnace and 2 a suitable receptacle or drum for containing the material to be dried, the furnace being adapted to furnish gases heated to the proper temperature for passage 75 through the receptacle or drum in order to effect the drying of the contents of the drum.

3 represents a suction fan, a stack or other means for withdrawing the moisture laden 80 gases from the drying receptacle and, in the 85 case of a beet pulp plant, for removing the light dry pulp from the drying chamber.

The rate at which the pulp dries is dependent upon the volume and the temperature of the gases passed over or through it. 90 The temperature is limited by the necessity for keeping the gases cool enough to avoid burning the pulp and consequently the volume of the heated gases is the only factor 95 which can be changed appreciably. Consequently the capacity of the drying plant and the efficiency for any given capacity depends directly upon the volume of hot gases which the furnace can deliver. Furthermore, such gases should be free from un- 100 consumed combustible material, that is, they should be as nearly smokeless as possible in order to avoid contamination or discoloration of the material which is being dried.

Heretofore the hot gases have been supplied from ordinary hand fired furnaces, the products of combustion flowing back through the drying receptacle; the blower or chimneys associated with the receptacles serving 105 not only to withdraw the moisture laden 110

gases but also to produce the requisite draft for causing the air to pass up through the grates so as to sustain combustion in the overlying bed of fuel. In such an arrangement the gases available for drying purposes are the combustion gases and the volume of these is definitely defined by the amount of air required to sustain satisfactory combustion. The volume of gases available for drying purposes can only be increased or decreased at the expense of a loss of efficiency in the furnace and with attendant smoke. Regulation of the volume of hot gases cannot successfully be obtained by drawing in free air independent of that coming through the grates to support combustion because an inlet for free air would disturb the draft conditions at the grate and would interfere with combustion, the ratio between the free air and the air passing through the grates depending upon the resistance encountered by the free air and that flowing through the grates. Even if an arrangement could be designed to produce a satisfactory proportion between the two streams of air under given conditions, it would be impossible even approximately to maintain such proportions since the condition of the fire is always changing, the depth of the fuel constantly varying and being different over different parts of the grate.

With a good fire, the gaseous products of combustion are much hotter than is necessary or practicable for drying purposes and therefore it is very desirable to have some means which will make it possible to reduce the temperature of the gases to the desired degree and at the same time utilize the excess heat for raising the temperature of air or other gases and make them available for drying purposes and it is to this end that my invention is directed. To attain this end I make use of apparatus which will make the process of combustion independent of the draft through the drying receptacle, thus making it possible to utilize this draft for the purpose of drawing in free air to be mixed with the combustion gases. By this means combustion and the amount of free air which is drawn in may be regulated independently of each other; the fire being always efficiently maintained at such a point as may be necessary to supply the requisite number of heat units to the drying gases, and the amount of free air being regulated so as to produce with the combustion gases the desired volume having the desired temperature.

In the furnace, instead of the old grates, I prefer to place the retorts and the dead plates of the well known Jones underfeed stoker, the number of retorts employed depending upon the size of the furnace. In the drawings I have illustrated a single arrangement in which there are in the furnace two

retorts 4, 4, the space between the retorts and surrounding the retorts between the walls of the furnace and the bridge wall 5 being filled with the usual dead plates 6. In this arrangement the chamber beneath the dead plates and extending from the front of the furnace to the bridge wall, as indicated at 7, forms an air chamber into which air is introduced by means of a suitable blower 8; the air passing up from this chamber through the twyer blocks 9 of the retorts as is usual in this type of stoker. Coal is fed from hoppers 10 in front of the retorts by means of the usual rams 11. As is customary with this type of stoker, the speed of the blower and the rate at which the rams are reciprocated are controlled so as always to provide the requisite feed of coal and supply of air for producing the amount of heat desired. The rear wall 12 of the furnace is arranged at some distance behind the bridge wall so as to provide behind the bridge wall what I shall term a mixing chamber. The top of the furnace is formed of the usual arch 13 above which is placed a roof or cover 14; the members 13 and 14 forming between them an air chamber 15. In the front wall of the furnace I provide one or more openings 16 which lead from the outside air into the chamber above the arch. In the rear wall 12 I provide a suitable conduit which communicates at its upper end with the chamber 15 and at its lower end with the interior of the furnace. In the arrangement shown, the conduit is made U-shaped as indicated at 17, one leg extending vertically through the wall near each side of the furnace and the lower ends of the two legs being connected together by a passage or conduit which opens forwardly into the furnace below the top of the bridge wall as indicated at 18. The wall 12 has an opening 19 therethrough for the passage of combustion gases from the furnace to the drying receptacle.

When the plant is in operation the fire burns in the presence of air supplied by the furnace blower and the gases of combustion are drawn back through the drying receptacle by the draft producing device at the outlet end of the receptacle. At the same time air flows from the outside through the opening or openings 16 in the front wall of the furnace and across the top of the heated arch, taking up heat from the arch in its passage and flowing down through the conduit 17 into the space within the furnace just back of the bridge wall and just below the outlet 19 for the combustion gases. The air rises and mixes with the combustion gases as they approach and while they are passing through the outlet 19, lowering the temperature of the combustion gases and increasing their volume so that the quantity of gas flowing through the drying appa-

ratus may be much greater than the amount of combustion gas passing from the furnace. It will be seen that the cold air in passing over the arch extracts heat therefrom, thus 5 keeping down the temperature of the arch and prolonging its life. There is consequently a saving not only of the heat units but also in the furnace structure itself.

If desired, the front wall of the furnace 10 may be provided with openings 20 controlled by suitable doors or covers 21 so that if a greater quantity of gas than that obtained in the manner heretofore described is desired, some or all of the doors or covers 21 15 may be wholly or partially opened, thus admitting additional free air into the system. This additional air which is admitted into the furnace directly over the fire has no disadvantageous effect on the fire because there 20 are no unconsumed volatile matters in the combustion gases which might be cooled sufficiently to form smoke, all of the volatile matters being driven out of the fuel in the retorts and being consumed as they rise into 25 the burning mass of fuel above.

While I have illustrated and described only a single preferred form of my invention, and one adapted for use in connection with an old form of drying receptacle, I do 30 not desire to be limited to the specific structural details thus illustrated and described,

to the use of my invention in connection with any particular form of drying receptacle, or to the field of drying beet pulp; for my invention is capable of many structural variations and is capable of use in various fields as will be evident from the definitions of my invention constituting the appended claim.

I claim:

In a drying plant, a furnace having a hollow top wall, the interior of said top wall communicating with atmosphere, a rear wall having an outlet through the center thereof for the passage of the combustion gases, 45 there being a conduit leading down through said rear wall from the interior of the top wall and opening into the furnace beneath said outlet, a bed in said furnace for supporting fuel, means for forcing the air necessary for combustion beneath said bed, a drying chamber connected with said furnace and adapted to receive the combustion gases flowing through said outlet, and means for producing a draft from the furnace through 50 said chamber.

In testimony whereof, I sign this specification in the presence of two witnesses.

WILLIAM J. KENNEY.
